DIFFERENTIAL VOLUME CONTROL FOR DIVERSITY RECEPTION

Application filed December 11, 1928. Serial No. 325,304.

This invention relates to diversity reception, and more particularly to a method and means for advantageously regulating the output from a plurality of antennas.

5 Short wave signals are subject to fading which varies both in frequency and degree in an unpredictable manner. Inasmuch as the fading at any instant may differ very widely at geographically spaced points, or 10 in different planes of polarization, it has been suggested that a receiving station be equipped with a number of antennas having different fading characteristics, the energies collected by which are fed to a single signal 15 responsive means.

Experience has shown that high frequency energy fluctuates not only in intensity but also in phase, and that there may be considerable relative phase fluctuation at the several antennas. This phenomenon makes it impossible to directly combine the radio frequency energies, for the energies may as often be in phase opposition as in like phase, to overcome this difficulty it has been suggested to equip each of the antennas with a separate receiver, and to combine the energies after rectification, and this, in the case of code signals, has proven an apt solution.

However, I have found that in the case of speech telephony, or other speech-simulating signals, where the transmission energy is radiated in the form of a carrier and side bands, there may be a relative difference in the phase fluctuations of closely adjacent frequencies, such as side band and carrier frequencies, even at one antenna, just as there is between carriers of like frequency at different antennas. This causes similar phase fluctuations in the beat of the carrier and side bands, for if of two beating waves one is kept constant in phase, while the other is shifted in phase, their beat is equally shifted in phase. It consequently follows 40 that although the carrier and side band energies experience only radio frequency differences in phase, these differences are transferred to the detected or audio frequency energies, so that it is as impossible to combine the detected energies as it is to directly

combine the originally collected radio frequency energies.

With the usual type of diversity system, even if applied merely to code signals, the received energy is apt to vary between the extremes of almost complete fading at all of the antennas to no fading at any of the antennas. To overcome this it has been suggested to employ a volume control with each antenna for varying the gain in the amplifier coupled thereto. Such an arrangement suffers from the disadvantage that the increased gain given an amplifier of an antenna at which fading is prevalent increases the noise level in the output of that amplifier, and therefore in the combined output of the entire system. Furthermore, in the case of speech-simulating signals, in the event of fading of the carrier and not of the side bands at an antenna its amplifier is given increased gain, as a result of which the beat between the side bands is unduly amplified before being combined with the output from the other antennas, thereby creating augmented distortion.

In order to overcome the foregoing difficulties I propose to select from among the several antennas that antenna at which the received signal is the strongest, and to amplify this signal, either exclusively, or at least predominantly, before using the collected energy for energizing the final signal responsive means. In this way there is little conflict due to relative phase fluctuations at the different antennas, and a considerable amount of volume control is provided merely in using substantially only one antenna at a time. Furthermore, an antenna at which the carrier alone has faded is given diminished output, and therefore has but little effect on the receiver, which reduces distortion.

In order to effect smooth operation, and to simplify the necessary apparatus, I do not physically disconnect all of the antennas but one, but rather permit them to remain in circuit, and regulate their outputs by controlling the amplification of their respective energies. In terms of a method, my invention includes simultaneously making a plurality of separate energy collections of relatively

different fading characteristics, preferably by collecting the energy on a plurality of geographically spaced antennas, separately amplifying each of the collected energies, controlling the gain in the aforesaid step of amplification of the energies in accordance with the amplitudes of the other energies, in order to strengthen the maximum signal or greatly magnify the ratio of the initial signal strengths, even to the point of completely cutting off a weaker signal, thereafter combining the energies, and translating the combined energy.

The foregoing method is unstable, because with even a very slight initial difference in the signal strength, the stronger signal is amplified, which then weakens the weaker signal, which then serves to more greatly amplify the stronger signal, so that almost instantaneously the weaker signal is completely cut out, while the stronger signal is greatly amplified. Thereafter the arrangement will not function to receive energy from the antenna which has been cut out, even though its signal should grow stronger, except if the signal on the antenna which before was a maximum should fade practically to zero, in which event the amplification gain is shifted rapidly, so as to greatly amplify the signal which then is a maximum. While this arrangement has the advantage of selecting the best antenna in a very positive manner, much like a mechanical relay, it has the great disadvantage of making the transition from one antenna to another distinctly audible, with a somewhat disturbing sudden change in volume.

To overcome this difficulty and make the change-over from one signal to another more stable and less noticeable, is a further object of my invention, which I accomplish by controlling the gain in the amplifiers only partially in accordance with the magnitude of the other energies, and partially in accordance with the magnitude of the energy being controlled. For this purpose I use a plurality of amplifiers with each antenna, and I couple the volume control means following the last amplifiers with amplifiers of corresponding antennas as well as with amplifiers of the other antennas. To more concretely fix the ideas involved, suppose two antennas are used. I then employ a first and a second electron emission tube amplifier for each of the two antennas, and I couple the volume control means following each of the second amplifiers with the first amplifiers of the corresponding antennas and the second amplifiers of the other antennas. In this manner the energy supplied to the translating device is kept constant by reason of the normal volume control operation of the first amplifier. However, if the signal should weaken so much that the first amplifier, when given maximum gain, still cannot keep the

signal up to the desired level, the second amplifier of the other antenna begins to be made conductive, and energy passing therethrough makes the second amplifier of the formerly active antenna grow non-conductive, and at the same time makes the first amplifier of the now active antenna attain such a bias as will supply the desired constant amount of energy to the translating device. The antenna which is cut out by reason of its second amplifier being negatively biased, at the same time has its first amplifier made highly conductive, which permits admission of the cut out signal in its turn with little or no initial difference in signal amplitude.

To attain substantial independence of the relative radio frequency phase at the different antennas it is desirable to combine the energies after rectification. At the same time, the volume control means preferably comprise detector tubes with impedances in their anode circuits from which the amplifier bias potentials are obtained through electrically slow circuits. For simplicity I combine the rectified energies obtained from the volume control detectors, thus dispensing with separate detectors, and this combination may best be made through coupling tubes connected to the detectors, the output of the coupling tubes being fed to a common translating device.

My invention is described more fully in the following specification, which is accompanied by a drawing in which Figure 1 is a wiring diagram for a form of my invention employing two antennas;

Figure 2 is a modification showing how my invention may be applied to a system having more than two antennas;

Figure 3 indicates an alternative form of bias lead connection when two antennas are employed; and

Figure 4 indicates an alternative form of bias lead connection when three antennas are employed.

Referring to Figure 1 of the drawing, there are a plurality of antennas 2 and 4, which are arranged to have different fading characteristics, either by being positioned in different planes of polarization or, more preferably, by being geographically spaced a substantial distance apart relative to the working wave length, or both. The antenna 2 is coupled by a transmission line 6 to a first amplifier 8, which in turn leads to a second amplifier 10, while the antenna 4 is coupled by a transmission line 12 to a first amplifier 14, which leads to a second amplifier 16. The amplified outputs are fed to detector tubes 18 and 20, which also act as volume control detectors. The anode circuits of the tubes include low pass filters 22 and 24, and sources of direct anode potential 26 and 28, and connected in series therewith, the coupling impedances 30 and 32, which complete

the anode circuits to ground. Arranged in parallel with the coupling impedances are electrically slow circuits comprising the resistances 34 and 36, in series with the condensers 38 and 40, the relative magnitudes of which determine the time constant of the volume control action.

From the volume control circuit 34, 38 a lead 42, 44 is led to the control electrodes of the tubes in the amplifier 16, while from the volume control circuit 36, 40 a lead 46, 48 is run to the control electrodes of the tubes in the amplifier 10. In this manner the amplifiers are made more or less conductive in accordance with whether the energies flowing through are greater or smaller, respectively, instead of vice versa as is ordinarily the case, so that the stronger signal is strengthened, the weaker signal is weakened and due to the cumulative action of this the amplifier of the weaker signal is soon sufficiently negative so that that signal is cut out.

This action is sufficiently abrupt and unstable to be noticeable to the ear, and to avoid this, I connect the volume control circuit 34, 38 by means of a lead 50 to the amplifier 8 and the volume control circuit 36, 40 by a lead 52 to the amplifier 14. This volume control functions in ordinary fashion, and serves to keep the volume of the signal being utilized at a desirable level, and at the same time, makes the change-over from one antenna to another practically unnoticeable because the final energy output to which the translating device is responsive is always kept at the desired signal level.

In order to couple the two receivers to a single translating means, which I shall term "combining the energies" even though one may be zero much of the time, the coupling impedances 30 and 32 are each led to coupling tubes 54 and 56 through blocking condensers 58 and 60. The control electrodes of the tubes are biased by batteries 62 and 64, and the anode circuits are connected together, as shown, and, through a transformer 66, to a common translating device here exemplified by a loud speaker 68. The anode circuit is then completed to a source of direct anode potential 70 and to ground.

My invention may be applied to systems having any number of antennas, it being necessary merely to provide a proper number of additional amplifiers. To illustrate this an arrangement with three antennas is shown in Figure 2, in which the three antennas 102, 104, and 106, are coupled by transmission lines 112, 114, and 116, to amplifiers 122, 124, and 126. These are followed by further amplifiers 132, 134, and 136, and 142, 144, and 146. The last amplifiers have coupled to them the rectifiers 152, 154, and 156, the anode circuits of which include volume control circuits 162, 164, and 166. The desired signal is fed to coupling tubes 172, 174,

and 176, the outputs of which are combined together and fed to a translating device 68. It will be observed that this arrangement is substantially like that shown in Figure 1 except for the addition of another set of amplifiers.

Inspection of the wiring diagram will show that each of the electrically slow volume control circuits are coupled to the control electrodes of the tubes in the corresponding first amplifier, and also to the control electrodes of the tubes in either the second or the third amplifier of the other antennas. Thus, with the maximum signal received on antenna 102, the volume control circuit 162 will bias the amplifiers 144, and 136 to cut off, while a maximum signal on the antenna 104 will cause the volume control circuit 164 to bias the amplifiers 142 and 146 to cut off, and a maximum signal on the antenna 106 will cause the volume control circuit 166 to bias the amplifiers 132 and 134 to cut off, so that at all times one of the signals will be amplified substantially to the exclusion of the other signals. Meanwhile the connections from the volume control circuits through which weaker signals are passing to the second and third amplifiers of the antenna collecting the maximum signal serve to boost the amplification gain of the maximum signal, resulting in a cumulative difference, as in the arrangement in Figure 1. However, instability is overcome by the bias leads running directly from each of the volume control circuits to the corresponding first amplifiers.

It is not essential that the bias lead connections be made exactly as in Figures 1 and 2. For example, the connections may be arranged as in Figures 3 and 4, in which all of the first amplifiers are coupled together and to a volume control unit, while all of the second amplifiers are coupled together and to a second volume control unit, and, in the case of Figure 4, all of the third amplifiers are coupled together and to a third volume control unit. Obviously, this arrangement also may be expanded to accommodate any desired number of antennas.

However, I consider that the arrangement shown in Figures 1 and 2, in which the true volume control action is applied to corresponding amplifiers, more specifically, to the first amplifiers, is slightly preferable because it permits of the use of a different number of stages of amplification in the first amplifiers, relative to the further amplifiers, should that prove desirable in order to attain smooth operation. Of course, the same result may be accomplished in the arrangements shown in Figures 3 and 4 by using the desired number of stages of amplification in that amplifier which is employed for direct volume control action, thus, in Figure 4, the first amplifier of the first antenna, the sec-

ond amplifier of the second antenna, and the third amplifier of the third antenna. However, this upsets the symmetry of the receivers, and furthermore, is complicated by the fact that the gain in an amplifier may differ, when receiving a large input, from the gain when receiving a very small input.

I claim:

1. The method of diversity reception which includes making a plurality of energy collections having different fading characteristics, separately amplifying each of the collected energies, controlling the gain in the aforesaid step of amplification of the energies partially in accordance with the magnitude of the other energies, and partially in accordance with the magnitude of the energy in question, in order to strengthen the maximum signal and to make the change over from one signal to another more stable and less noticeable, combining the energies, and translating the combined energy.

2. The method of diversity reception which includes making a plurality of energy collections having different fading characteristics, separately amplifying each of the collected energies, separately further amplifying each of the amplified energies, controlling the gain in the first step of amplification in accordance with the corresponding final output, controlling the gain in the further amplification in accordance with the output of the other energies, combining the final output energies, and translating the combined energy.

3. The method of diversity reception which includes making a plurality of energy collections at geographically spaced points, separately amplifying each of the collected energies, separately further amplifying each of the amplified energies, controlling the gain in the first step of amplification in accordance with the corresponding final output, controlling the gain in the further amplification in accordance with the output of the other energies, combining the energies, and translating the combined energy.

4. The method of diversity reception which includes making a plurality of energy collections of different fading characteristics, separately amplifying each of the collected energies a plurality of times, rectifying the amplified energies, controlling the gain in some of the steps of amplification in accordance with the amplitude of the corresponding rectified energy, controlling the gain in the other steps of amplification in accordance with the amplitude of the other rectified energies, combining the rectified energies, and translating the combined energy.

5. The method of diversity reception which includes making a plurality of energy collections at geographically spaced points, separately amplifying each of the collected energies, separately further amplifying

each of the amplified energies, rectifying the amplified energies, controlling the gain in the first step of amplification in accordance with the amplitude of the corresponding rectified energy, controlling the gain in the further amplification in accordance with the amplitude of the other rectified energies, combining the rectified energies, and translating the combined energy.

6. A diversity receiving system comprising a plurality of antennas having different fading characteristics, an amplifier coupled to each of the antennas, volume control means following each of the amplifiers, and means so coupling each of the volume control means to the amplifiers as to control the gain in the amplifiers partially in accordance with the magnitude of the energies from the other amplifiers, and partially in accordance with the magnitude of their own outputs, in order to strengthen the maximum signal and to make the change-over from one signal to another more stable and less noticeable, means to combine the volume controlled energies, and means to translate the combined energy.

7. A diversity receiving system comprising a plurality of geographically spaced antennas, an amplifier coupled to each of the antennas, further amplifiers coupled to each of the first amplifiers, a rectifier coupled to each of the last amplifiers, a volume control impedance in each of the rectifier circuits, means coupling the volume control impedances to corresponding first amplifiers and to the further amplifiers of the other antennas, means to combine the rectified energies, and means to translate the combined energy.

8. A diversity receiving system comprising two geographically spaced antennas, an electron emission tube amplifier coupled to each of the antennas, a second electron emission tube amplifier coupled to each of the first amplifiers, a detector coupled to each of the second amplifiers, a volume controlling bias lead connected from the anode circuit of each of the detectors to the control electrodes of the tubes in the corresponding first amplifier and to the control electrodes of the tubes in the other second amplifier, means to combine the rectified energies, and means to translate the combined energies.

9. A diversity receiving system comprising two geographically spaced antennas, an electron emission tube amplifier coupled to each of the antennas, a second electron emission tube amplifier coupled to each of the first amplifiers, a detector coupled to each of the second amplifiers, a volume controlling bias lead connected from the anode circuit of each of the detectors to the control electrodes of the tubes in the corresponding first amplifier and to the control electrodes of the tubes in the other second amplifier, a coupling tube connected to each of the detectors, a translating device, and means coupling the anode

circuits of the coupling tubes together and to the translating device.

10. A diversity receiving system comprising three geographically spaced antennas, an electron emission tube amplifier coupled to each of the antennas, second and third electron emission tube amplifiers coupled to each of the first amplifiers, a detector coupled to each of the third amplifiers, a volume control bias lead connected from the anode circuit of each of the detectors to the control electrodes of the tubes in the corresponding first amplifiers and to the control electrodes of the tubes in one of the second and third amplifiers of the other antennas, a coupling tube connected to each of the detectors, a translating device, and means coupling the anode circuits of the coupling tubes together and to the translating device.
